VACUUM CLEANER FILTER

Tord Erik Daniel Bilde, Stockholm, Sweden, assignor to Electrolux Corporation, Dover, Del., a corporation of Delaware

Application March 3, 1937, Serial No. 128,705
In Germany March 6, 1936

3 Claims. (Cl. 183—71)

My invention relates to vacuum cleaner filters and more particularly to an improved filter and its arrangement in combination with a vacuum cleaner unit.

5 One of the objects of my invention is to provide a filter of comparatively small size, but having a large filtering area. In accordance with my invention, the filter cloth or other filtering material, is given an undulated form in order to 10 accomplish the last mentioned object. In order that the construction of the filter will be simple the undulations are located parallel to one side of the filter cloth, thus making possible the use of a rectangular piece of material and avoiding the necessity of cutting it into odd shapes. This also eliminates waste of material.

Another object of my invention is to provide a filter which may be readily removed from the vacuum cleaner unit, for the purpose of cleaning or replacing it, without requiring the use of any special tool or the like.

Further objects and advantages of my invention will be apparent from the following description when considered in connection with the accompanying drawings, which form part of this specification and of which—

Fig. 1 is a cross-sectional view of one embodiment of my invention;

Fig. 2 is a perspective view of the filter shown in Fig. 1;

Fig. 3 is a cross-sectional view taken on the line 3—3 of Fig. 1;

Fig. 4 is a cross-sectional view of a second embodiment of my invention;

Fig. 5 is an end view of the filter shown in Fig. 4, and

Fig. 6 is a side view, partially broken away of the filter shown in Figs. 4 and 5.

Referring more particularly to Fig. 1, reference character 10 designates generally the casing of a vacuum cleaner unit. Casing 10 includes a cylindrical portion 11 and end caps 12 and 13. End cap 12 is formed with a threaded inlet opening 14 which is adapted to receive a hose or suction conduit 15, leading to a suction nozzle 16. A rigid tubular handle member 17 may be interposed between hose 15 and nozzle 16. Disposed within casing 10 is a dust separating member 18, here shown in the form of a bag secured to a ring 19.

50 Ring 19 has an outwardly extending flange which is adapted to be clamped between cap 12 and the end of cylindrical portion 11, when the cap is secured in place, as by means of spring clips 20.

The opposite end of cylindrical portion 11 includes a ring 21, preferably made of insulating

material such as "Bakelite", which supports a motor fan unit 22. Likewise secured to ring 21 is a hood member 23 formed with openings 24 therethrough. Hood member 23 is thus fixed within the casing and serves as a guard for the 5 electric motor when the end cap 13 is removed.

The end cap is formed with an exhaust opening 25 which may be threaded to receive hose 15 and across which opening extend inclined vanes 26. The center vane is formed as a bushing 27 through which extends a rod 28, the outer end of which is formed with a knurled knob 29. The opposite end of rod 28 is threaded and is adapted to engage a threaded member 30 fixed to hood member 23. Thus, rod 28 serves to secure 10 end cap 13 in place. The end cap may be removed by merely unscrewing the rod from member 30.

Reference character 31 designates generally my improved filter. The filter includes a base portion 32 made of cardboard, wood or other suitable cheap and fairly stiff material. Secured to opposite ends of base portion 32, or integral therewith, are end portions 33, the edges of which are deeply notched as is shown at 34. A piece of filter cloth, or other suitable flexible filtering material 35 having initially a rectangular shape, has one edge 36 secured to one side of base portion 32. The edges of filter cloth 35 which extend at right angle to edge 36 are supported 30 from end portions 33, while the other edge is secured to the opposite side of base portion 32. The filter cloth may be secured to the base and end portions by being glued thereto. The notched edges of the portions 33 result in an undulated 35 surface of the filter cloth.

The central portion of the undulated surface is formed with an opening 37 through which rod 28 is adapted to extend. The rod is formed with a collar 38 which serves to hold this portion of 40 the filter cloth tightly against member 30, thus preventing passage of air through the opening 37.

Base portion 32 is formed with a large opening 39 which is adapted to embrace an annular member 40 secured to the end cap 13 around the 45 exhaust opening 25. Member 40 serves to support the base member and to prevent the passage of air from within cap 13 to the opening 25 without the air having passed through the filter.

In order to prevent fluttering of the central 50 portions of the filter material, which might result in the passage of dirt particles, members 42 extending through the troughs of the undulations may be provided. Members 42 are resilient and bowed downwardly at 43 so as to hold the filter 55

material taut. The resilient ends 44 of members 42 are arranged to snap over the end portions 33, thus holding the members in place.

In operation the rotation of the motor fan unit serves to draw air inwardly through nozzle 16, hollow handle 17, and hose 15 to the interior of dust bag 18. As the nozzle is passed over a dusty surface, dust is entrained with this air. All but the very finest particles of dust are separated from the air stream by the dust bag 18 and are retained therein. The air and possibly the very finest particles of dust pass through the bag and are discharged from the motor fan unit through the openings 24 in hood 23 to the interior of cap 13. The air then is forced to pass through the filter material 35 to the space within the filter from where it passes through opening 29 and exhaust opening 25 to the atmosphere. Due to the very large surface of the filter material resulting from its undulated shape, this material offers very little resistance to the passage of air. The nature of this material is such that it separates the very finest dust particles, as well as bacteria. It also serves to deaden the noise resulting from the operation of the motor fan unit.

In the event that it is desired to remove the filter 31 for the purpose of cleaning it or replacing it with a new one, rod 28 is rotated by means of knob 29 so as to disengage the threaded end of the rod from member 30. End cap 13 may then be removed and the filter 31 may be removed from the end cap.

In the embodiment shown in Figs. 4 through 6, the filter consists of a pair of spaced circular discs 50 and 51, the outer edges of which are notched. These discs may be held in spaced relation by means of spacer members 52. Filter material 53 is supported between the notched edges, which give it an undulated surface. In this case, the filter material initially has a rectangular shape before being secured to the discs.

Disc 50 is provided with a small aperture 54 through which extends rod 28, while disc 51 is formed with a large aperture 55 which embraces the member 40 which is secured to the end cap.

The operation of this embodiment is substan-

tially the same as that described in connection with the first embodiment. The air, after it is passed through openings 24 in hood 23, passes radially inwardly through the filter material 53 to the interior of the filter, from where it passes through opening 55 to the exhaust opening 25. In this embodiment it will be noted that the filter is clamped between the cap 13 and the hood 23 when the latter is secured in place, thus assuring that all of the air passes through the filter. The filter may be removed by unscrewing rod 28 to thereby release the end cap. After the end cap has been removed, the filter may be removed therefrom and cleaned or replaced by a new one.

While I have shown two more or less specific embodiments of my invention, it is to be understood that this has been done for purposes of illustration only and that the scope of my invention is not to be limited thereby, but is to be determined by the appended claims viewed in the light of the prior art.

What I claim is:

1. In a filter for a vacuum cleaner, a pair of spaced discs formed with notched edges, and filter material supported between said edges, whereby said material is formed with an undulated surface one of said discs being perforate and the other disc being imperforate.

2. In a filter for a vacuum cleaner, a first disc, a second disc, the edges of said discs being notched, and filter material secured between said notched edges and following the contours thereof, whereby the surface of said material is undulated, one of said discs being formed with an opening communicating with an exhaust opening of the vacuum cleaner.

3. In a filter for a vacuum cleaner, a plurality of air impervious walls, said walls extending parallel to each other and formed with notched edges, and filter material supported between said notched edges whereby the surface of said material is undulated, one of said walls being formed with an aperture communicating with an outlet opening in the vacuum cleaner.

TORD ERIK DANIEL BILDE.
